YORK, A CORPORATION OF NEW YORK

ELECTRICAL SWITCH

Application filed November 4, 1927. Serial No. 231,059.

This invention relates to electrical switches, and more particularly to the type generally known as snap switches.

An important object of the invention is to provide a switch of the above character in which the parts thereof are constructed in a manner to reduce the cost of manufacture and assembly, and yet result in a switch which is highly efficient in use, durable and can be readily dismantled for repairs if necessary.

Another important object is to provide a construction for floating the movable contact blade of the switch and for limiting its lateral movements, whereby it will at all times properly engage with the cooperating stationary contacts to form a sure and positive electrical connection.

Another object of the invention is to provide an insulating block or base provided with seats directly in the walls thereof for mounting an oscillatory actuator of a switch blade, the block also being equipped with walls constituting spaced abutments for limiting the throw of the oscillatory actuator.

A further object of the invention resides in the provision of an insulator block or base having grooves for the reception of the depending portions of a bridge piece which carries part of a toggle mechanism, said grooves facilitating assembly of the switch and insuring proper positioning of the component parts of the switch mechanism, as well as serving to rigidify the connection of the bridge piece with the insulator base, while other grooves serve to confine a part of the switch mechanism in its proper plane of actuation.

Other objects and advantages of the invention will become apparent during the course of the following description.

In the drawings forming part of the application, and wherein like numerals are employed to designate like parts throughout the several views:

Figure 1 is a top plan of our improved switch.

Figure 2 is a longitudinal section through the same, looking at one side thereof.

Figure 3 is a similar view, looking toward the opposite side.

Figure 4 is a transverse section of the same at substantially the medial portion thereof.

Figure 5 is a top plan of the insulator base, and

Figure 6 is an exploded perspective view of the switch blade and oscillatory actuator element.

Referring now more particularly to the drawings, wherein one example of the switch is illustrated, the numeral 7 designates a base or support of insulating material, preferably porcelain. A very detailed description of this base is essential for an appreciation of its cooperation both in the assembly and operation phases of the invention, and, consequently, such description is given. This base is provided with a T-shaped recess 8 for the reception of an actuating mechanism and switch blade to be presently described, and its cross arm is formed by a relatively narrow recess or chamber 9 extending longitudinally of the block for the reception of the switch blade, it being noted that the opposed walls 10 of the narrow recess 9 are arranged in rather close proximity for a purpose which will become apparent during the course of the following description.

The outer surface 11 of the block or support 7 beyond opposite ends of the narrow recess 9 is provided with recesses 12 and 13 for the reception of stationary contacts 14 and 15, having the usual screw binding posts, and are secured in said recess by means of screws 16 extending through the block from the back thereof, as shown. The stationary contact 14 is provided with a depending extension 17 which projects down into one end of the narrow recess 9 to terminate in a contact portion 18 arranged at the bottom of the recess and extending longitudinally thereof, as best shown in Figure 3. The other stationary contact is provided with an angularly disposed contact portion 19 which projects longitudinally into the other end of the narrow recess 9 at the top thereof.

- The interior surfaces of opposite walls of the recess 8 are each equipped with an inwardly extending groove or slot 20 having a V-shaped bottom or inner end 21. These slots open out into the outer face 11 of the block 7 and are arranged directly opposite each other to form bearings for a part of the actuating mechanism which will be later described.
- 10 It will be noted that the other two opposed walls of the recess or cavity 8 are provided with steps, the lowermost ones 23 forming abutments for the mechanism, as will be more fully described hereinafter.
- 15 These opposed walls of the recess 8 are also provided with recesses 24 which have relatively narrow slots or grooves 25 arranged in alignment longitudinally of the block for guiding a part of the actuating mechanism
- 20 and restraining its lateral play. A pair of apertures 26 extend through the insulating block 7 from its back to its outer face, and are arranged in longitudinal alignment with the slots 25. The ends of these apertures 25 at the back of the block are countersunk as at 27 to receive the heads of screws 28, the purpose of which will be presently described. The outer face 11 of the block is also provided on opposite sides of the slots 25 with a pair of spaced parallel grooves 29 extending longitudinally thereof.

The actuating mechanism for the switch consists in part of an oscillatory switch blade actuator 30 assuming the form of a flat U-shaped piece of material having its bridge portion provided with a projection 31. This U-shaped piece may be stamped from sheet metal, or if desired, from sheet insulating materials. The two legs of the element 30 are provided with lateral extensions 32 and 33 adapted to have their lower edges rest upon the V-shaped portions of the slots 20 in the opposite walls of the block 7. It will be noted that the lateral extension 32 is longer than its brother 33, so that it will extend transversely through the narrow recess 9 of the block. An advantage accrues to the construction of this element 30 out of sheet material, in that its edges are utilized to form thin edged supports to minimize frictional resistance to its free oscillatory movement.

On the lateral extension 32 of the oscillatory element 30 is floated a movable contact or switch blade 34 by mounting it upon a non-circular insulator block 35 provided with an elongated narrow opening 36 extending through opposite faces thereof and having a metallic U-shaped bushing 37 through which the flat lateral extension is adapted to extend. The fit between the bushing 37 and the lateral extension 32 is such as to permit the insulator block 35 to have slight lateral movement upon the extension 32. From Fig. 1 it will be noted

that the insulator block 35 is slightly narrower than the width of the recess 9, and it will be seen that lateral movement of this block between certain limits is restrained by the block 35 engaging the inner wall of the recess 9 at one side and a depending leg of the oscillatory element 30 at its opposite side.

This insulator block 35 obviously insulates the switch blade 34 from the actuating mechanism. It will, of course, be understood that the insulator block 35 may be dispensed with entirely, or non-insulating material employed if the oscillatory element 30 is formed of insulating material as pointed out before.

The switch blade 34 in the present instance is composed of a folded copper blank giving the blade double thickness so that each of the arms 38 of the blade may be economically composed of a pair of spring strips, the free ends of each being equipped with laterally extended tabs 39 to provide opposite edges of each arm 38 with two pairs of outwardly diverging wings 40 to facilitate the switch blade sliding over and gripping the stationary contacts 18 and 19. The medial portion of the switch blade 34 is enlarged and is provided with a non-circular opening 41 slightly larger than and conforming to the configuration of the external surface of the insulating block 35, so that it may be easily slipped upon this block and have a slight amount of lateral play thereon. If the oscillatory element 30 is constructed from insulating material as suggested previously, the opening 41 in the switch blade is made to conform to the cross-section of the extension 32 so as to have a floating connection therewith.

With the foregoing construction, it will be seen that the switch blade is floated upon the extension 32 within the recess 9 and has considerable lateral movement on this extension, such movement being limited by the switch blade contacting with opposed walls 10 of the recess adjacent its ends. Such construction renders the switch blade self-aligning with the stationary contacts 18 and 19 thereby eliminating assembly precautions in setting the parts in exact alignment for proper engagement of the movable switch blade with its stationary contacts.

In assembling the oscillatory U-shaped member 30 with the associated insulating block 35 and switch blade on its lateral extension 32, is simply dropped into the T-shaped recess 8 of the base 7, so that the lateral extensions 32 and 33 seat on the V-shaped bottoms of the slots 20 in the base, with the switch blade and insulator block disposed in the relatively narrow recess 9. The oscillatory movement of the element 30 is limited by the bridge portion thereof engaging the opposed walls 23 of the recess 8,

and it will be noted that this bridge portion does not contact with the bottom of the recess 8; the sole support of the oscillatory element 30 being obtained by the extensions 5 or trunnions 32 and 33 resting directly upon the bottoms of the grooves 20 formed directly in opposed walls of the insulator support 7.

This U-shaped element 30 is oscillated by 10 the action of a compression spring 42 and a rocker lever 43, one end of the spring receiving the extension 31 and seating on the bridge portion of the U-shaped element 30, while the other end of the spring 42 is 15 threaded through an eye in a depending portion 44 of the lever 43.

This lever 43 is fulcrumed on the pin 45 which is extended through aligned openings in spaced parallel depending flanges 46 bent 20 from the intermediate portion of a bridge piece 47 provided with a central opening 48 for the projection therethrough of an extension 49 of the lever 43. This extension 49 forms the actuating handle and is prefer- 25 ably constructed of insulating material and has the lever 43 embedded therein or secured thereto in any suitable manner. From Fig. 2, it will be observed that the operating lever 43 is provided at both sides of its fulcrum 30 with extensions 50 projecting beyond opposite ends of the face of the handle 49 for abutment with the under side of the bridge piece 47 at opposite ends of the opening 48 therein to limit the oscillation of the lever.

35 Rapid assembly of the switch can be performed by simply dropping the element 30 and associated switch blade into its bearings as stated before.

Then the bridge piece 47 with its associated lever 43 is placed upon the block 7 with its flanges 46 in the grooves 29 which will align the spring 42 with the extension 31 of the element 30 so that pressure upon the bridge piece will seat the spring upon the 45 extension 31 and tension the spring 42 between the lever 43 and the oscillatory element 30. Screws 28 are then passed through the base 7 and turned into threaded apertures 51 in the bridge piece so as to complete 50 the assembly of the switch. With the parts thus quickly assembled with a minimum number of operations and screws, it will be noted that the lateral extensions 50 of the operating lever 43 will operate in the 55 aligned slots 25 of the base, and will thereby be limited in its lateral play.

From the foregoing description, it will be seen that the compression spring will be compressed by throwing the handle 49 to one side or the other, at which time the spring rapidly expands under the energy stored up by compression and snaps the oscillatory member to one side or the other of its central position, thereby causing a 65 quick engagement or disengagement of the

switch blade with the stationary contacts. It will be recalled that the oscillatory movements of the U-shaped element 30 are limited by its contact with the opposed walls 23 of the cavity 8, while the rocking movements of the lever 43 are limited by engagement of the extensions 50 with the under face of the bridge piece 47, thereby keeping the compression spring confined between these two levers at all times.

It is, of course, apparent that a two blade switch can be provided by simply extending the extension 33 and mounting a second switch blade 34 thereon to cooperate with a second pair of stationary contacts.

From the foregoing description, it will be obvious that the switch can be assembled rapidly and without exercising precautions to get the parts in their proper relative positions with the minimum number of fastening devices, due to the cooperation of the various parts of the actuating mechanism with the insulating base 7.

We claim:

1. A snap switch comprising a support, a pair of contacts, an actuating mechanism including an oscillatory U-shaped element having a lateral extension, an insulator having floating connection with said lateral extension and having lateral movement restrained by contacting with a wall of said support and said U-shaped element, and a contact blade mounted upon said insulator.

2. A snap switch comprising a support, a pair of contacts, an actuator mechanism including an oscillatory element, an insulator mounted on an end portion of said element, a metallic bushing in said insulator, and a switch blade mounted upon said insulator.

3. A snap switch comprising a support of insulating material, a pair of contacts, a substantially U-shaped oscillatory member having laterally extending arms fulcrumed in said support, a movable contact blade detachably connected to one of said arms, spring and lever means for actuating said oscillatory member, and said movable contact blade being insulated from said spring and lever means.

4. A snap switch comprising a support of insulating material, a pair of contacts, a substantially U-shaped oscillatory member having laterally extending arms fulcrumed in said support, a movable contact blade carried by said oscillatory member, spring and lever means for actuating said oscillatory member, said movable contact blade being insulated from said spring and lever means and having a floating mounting on said oscillatory member.

5. A snap switch comprising a support of insulating material, a pair of contacts, a substantially U-shaped oscillatory member having laterally extending arms fulcrumed in said support, a movable contact blade

carried by said oscillatory member, spring and lever means for actuating said oscillatory member, said movable contact blade being insulated from said spring and lever means and having a floating mounting on said oscillatory member and means co-acting with opposite sides of said blade for limiting its lateral movement.

6. A snap switch comprising an insulator block having bearings, a pair of contacts, an actuator mechanism including an oscillatory element having flat extensions forming thin edged trunnions seated in said bearings, and a switch blade detachably connected to one of said trunnions.

7. A snap switch comprising an insulator block having bearings on its inner walls, a pair of contacts, an actuator mechanism including a substantially U-shaped flat oscillatory element having at its upper end laterally extending trunnions extending into said bearings and supported by their edges therein, and a switch blade detachably connected to one of said trunnions.

8. A snap switch comprising an insulator block having bearings on its inner walls, a pair of contacts, an actuator mechanism including a substantially U-shaped flat oscillatory element having at its upper end laterally extending trunnions extending into said bearings and supported by their edges therein, and a switch blade detachably connected to one of said trunnions.

9. A snap switch comprising an insulator block having bearings on its inner walls, a pair of contacts, an actuator mechanism including a substantially U-shaped flat oscillatory element having at its upper end laterally extending trunnions extending into said bearings and supported by their edges therein, and a switch blade carried on one of said trunnions between its end and an arm of said U-shaped element.

10. A snap switch comprising an insulated support having V-shaped seats in opposite walls thereof, a pair of stationary contacts, an actuator mechanism including an oscillatory element having substantially knife edge extensions fulcrumed in said seats, and a switch blade detachably connected to one of said extensions.

11. A snap switch comprising an insulated support having open ended grooves in opposite walls thereof to provide seats, a pair of contacts, an actuator mechanism including an oscillatory element and a spring, said oscillatory element being fulcrumed in said seats, said spring tending to retain said oscillatory element engaged with said seats, a switch blade detachably connected to said element, and said grooves opening in the direction of said actuator mechanism.

12. A snap switch comprising a support of insulating material having seats in opposed walls thereof, a pair of contacts, an

actuator mechanism including a rocker lever and an oscillatory element, said oscillatory element being fulcrumed in said seats, a compression spring interposed between said rocker lever and said oscillatory element serving to retain said oscillatory element in said seats, and a contact blade detachably connected to said element.

13. A snap switch comprising an insulator support having an actuator mechanism receiving a recess provided with opposed abutment walls, a pair of contacts, an actuator mechanism including a U-shaped oscillatory switch carrying element having trunnions mounted in the walls of said insulator support and adapted to abut said abutment walls to limit the oscillatory movement of said element, and a contact blade detachably connected to one of said trunnions.

14. A snap switch comprising a support of insulating material having a pair of parallel grooves, an actuator mechanism mounted in said support and including a bridge having a depending flange adapted to be received in said grooves, and means for securing said bridge to said support.

15. A snap switch comprising a support of insulating material having an actuator mechanism receiving recess therein, and a pair of grooves extending therefrom, a bridge having a depending flange to be received in said grooves, an actuator mechanism mounted in said recess and including an oscillatory element fulcrumed directly in opposed walls of said recess, a rocker lever mounted in said bridge, a compression spring interposed between said lever and element, and means for securing said bridge to said support.

16. A snap switch comprising a support of insulating material having an actuator mechanism receiving recess therein, opposed walls of said recess having aligned slots, a bridge secured to said support, and a toggle switch mechanism mounted in said recess and including a rocker lever having extensions operating in said slots and adapted to abut said bridge.

17. A snap switch comprising a support, a pair of contacts, an actuating mechanism including an oscillatory element, a non-circular insulator loosely mounted upon said element, and a contact blade having an opening receiving said insulator for mounting the same.

18. A snap switch comprising an insulating support having opposed seats in the walls thereof, a pair of contacts, an actuator mechanism including a U-shaped oscillatory element fulcrumed in said seats, and a switch blade detachably connected to an end portion of said element.

19. A snap switch comprising an insulating support, a pair of contacts, an actuator mechanism including a U-shaped oscillatory

element having laterally extending trunnions fulcrumed for support, said element being of insulating material, and a switch blade carried by one of said trunnions for cooperation with said contacts.

5 20. A snap switch comprising an insulating support having seats in opposite walls thereof, a pair of contacts, an actuator mechanism including a U-shaped oscillatory element having flat laterally extending trunnions fulcrumed in said seats in said support, said element being of insulating material, and a switch blade carried by one of said trunnions for cooperation with said contacts.
